US00D872508S

(12) **United States Design Patent** (10) Patent No.: **US D872,508 S**
(45) Date of Patent: ** Jan. 14, 2020

(54) **RETAIL DISPLAY**(71) Applicant: **Apple Inc.**, Cupertino, CA (US)(72) Inventors: **Alice Marlin Brugger**, San Francisco, CA (US); **Joshua Robert Edwards**, Santa Cruz, CA (US); **Jean-Marc Gady**, Los Altos, CA (US); **Moritz Wilsberg**, Menlo Park, CA (US)(73) Assignee: **Apple Inc.**, Cupertino, CA (US)(***) Term: **15 Years**(21) Appl. No.: **29/694,970**(22) Filed: **Jun. 14, 2019****Related U.S. Application Data**

(63) Continuation of application No. 29/650,766, filed on Jun. 8, 2018, now Pat. No. Des. 851,428, which is a continuation of application No. 29/599,805, filed on Apr. 6, 2017, now Pat. No. Des. 820,619.

(51) **LOC (12) Cl.** ..... **06-06**(52) **U.S. Cl.**USPC ..... **D6/675.1**(58) **Field of Classification Search**USPC D6/672, 673, 675-675.1, 675.3, 675.4
CPC .. A47F 1/00; A47F 5/0081; A47F 5/04; A47F

(57)

CLAIM

The ornamental design for a retail display, as shown and described.

DESCRIPTION

FIG. 1 is a top front perspective view of a retail display showing the claimed design;

FIG. 2 is a bottom front perspective view thereof; and,
FIG. 3 is a front view thereof.**1 Claim, 3 Drawing Sheets**| (56)	References Cited
